[57] CLAIM

The ornamental design for a separating tool for toy building elements, as shown and described.

DESCRIPTION

FIG. 1 is a top perspective view of a separating tool for toy building elements showing our new design;
FIG. 2 is a bottom perspective view thereof;
FIG. 3 is a side elevational view thereof, the side opposite being substantially a mirror image;
FIG. 4 is a front elevational view thereof;
FIG. 5 is a rear elevational view thereof;
FIG. 6 is a top plan view thereof; and,
FIG. 7 is a bottom plan view thereof.

FIG. 5

FIG. 7

FIG. 3

FIG. 6

FIG. 4
